UNITED STATES PATENT OFFICE

PETER THATCHER COOK, OF SAUSALITO, CALIFORNIA

DESIGN FOR A BIRD HOUSE

Application filed May 31, 1932. Serial No. 43,937. Term of patent 3½ years.

To all whom it may concern:

Be it known that I, PETER THATCHER COOK, a citizen of the United States of America, and a resident of Sausalito, county of Marin, State of California, have invented a new, original, and ornamental Design for a Bird House, of which the following is a specification, reference being had to the accompanying drawing, forming part thereof.

I claim:

The ornamental design for a bird house, substantially as shown.

In testimony whereof, I have hereunto set my hand.

PETER THATCHER COOK.
